COKING HYDROCARBON OIL

Donald L. Thomas, New York, N. Y., assignor to
Gasoline Products Company, Incorporated,
Newark, N. J., a corporation of Delaware

Application September 13, 1933, Serial No. 689,254

4 Claims. (Cl. 202—18)

This invention relates in general to carbonizing fuel and more especially to an improvement in the art of coking hydrocarbon oil.

My invention is particularly adapted to be used in conjunction with a cracking process wherein the cracking and distillation of the charging stock are carried on separately from the coking of the residuum produced during the operation, which latter operation is conducted in a separate piece of apparatus whose temperature may be independently controlled.

My invention contemplates withdrawing hydrocarbon oil residuum produced in a combined distilling and cracking operation and introducing it, while in a heated condition, into contact with a bath of molten metal maintained in an enlarged coking still. The heat transferred to the residuum from the bath of molten metal decomposes it to coke which collects on the surface of the molten metal bath to be removed from the coking still either continuously or intermittently. Volatile constituents of the residuum may be separately removed, fractionated and condensed. Any liquid residuum adhering to the coke may be removed therewith and thereafter filtered out.

In order to make my invention more clearly understood, I have shown in the accompanying drawing, an apparatus for carrying the same into practical effect without limiting the improvements in their useful applications to the particular constructions which, for the purpose of explanation, have been made the subject of illustration.

Figure 1 is an elevational view of an apparatus, partly in section, capable of carrying out the invention.

Figure 2 is a horizontal cross-sectional view taken along line 2—2 of Figure 1.

Figure 3 is a horizontal cross-sectional view taken along line 3—3 of Figure 1.

Referring to the figures and more particularly to Figure 1, there is shown a main vaporizer 1 for receiving oil to be distilled and a stream of oil that has been subjected to cracking. A separately fired coking still 2 and a coke filter 3 are associated with the vaporizer 1, the filter 3 separating uncooked residuum from the coke discharged from the coking still 2 to permit the return thereof, as will be hereinafter explained, for further treatment.

The vaporizer 1 may consist of a vertically placed steel drum of any suitable dimensions. This drum, for instance, may be about six feet in diameter and from about ten to fifteen feet in

height. In the upper portion of the vaporizer 1, there is located a circular cone shaped baffle plate 4, firmly attached to a steel spider 5. The diameter of the circular baffle plate 4, which is centrally placed with reference to the vaporizer 1, is somewhat less than that of the vaporizer shell thereby providing an unobstructed annular space between the shell and the baffle plate 4 for the free passage of hydrocarbon oil and gases. The annular space provided between the baffle plate 4 and the shell may in actual construction be about 6 inches in width.

A conical member 6 may be located in an inverted position above the baffle 4 and may be suitably joined to the sides of the vaporizer 1 to 15 shut off the upper portion thereof except for a central opening 7. This central opening 7 is of materially less diameter than the baffle plate 4, so that any liquid discharged therethrough will fall on the baffle plate 4 and be distributed there- 20 by around the sides of the vaporizer shell to pass through the aforementioned annular space between the vaporizer shell and the baffle plate 4.

By the construction just described, there is formed a space 8 in the upper portion of the 25 vaporizer into which crude primary charging stock to be distilled may be delivered by way of a pipe 9 controlled by a suitable valve 11. The charging stock introduced through the pipe 9 passes through the opening 7 on to the baffle 30 plate 4 by which it is distributed around the sides of the vaporizer.

A tubular distributing member 12, having four radially extending arms 13, may be located within the lower portion of the vaporizer 1. The radially extending arms 13 may be provided on the upper side of each with a plurality of conical nozzles 14 communicating with the interior of each arm in order that any liquid entering the arms 13 will be discharged through the nozzles 14 in an upward direction. An overflow pipe 15 may be centrally positioned in the tubular distributing member 12 and suitably welded thereto. The overflow pipe 15 may be spaced from the walls of 40 the distributing member 12 to leave an annular space between the two in order that fluid delivered to this space by means of an oil pipe 16 controlled by valve 17, may enter the radial arms 13 of the member 12 and be discharged through the conical nozzles 14 as clearly shown in Figure 1. The overflow pipe 15 is preferably arranged to maintain a considerable depth of liquid over the nozzles 14 so that when fluid is forcibly ejected from these nozzles in an upward direction it will carry 45 50 55

along with it overlying layers of liquid maintained in the bottom of the vaporizer 1.

The fluid introduced through the pipe 16 to be ejected from the nozzles 14 may be the hot cracked stock coming from an oil cracking operation, for example, it may comprise the total stream of cracked products issuing from a cracking coil or passageway. The crude oil introduced into the upper portion of the vaporizer 1 through the line 10 9 will be subjected to intense and continually repeated contact with the upwardly rising vapors from the cracked stock in a somewhat spray form, thus bringing about rapid distillation of the liquid, the vapors from which, together with the 15 cracked vapors, escape to a suitable rectifying and fractionating tower, not shown, through an opening 18 at the top of the vaporizer. The central position of the overflow pipe 15 insures that all of the liquid entering the vaporizer shall at some 20 time be brought under the entraining action of spraying jets thus insuring that no untreated residuum shall pass out through the overflow.

Valve 17 should be adjusted as necessary and optionally automatically to maintain a sufficient 25 pressure in the radial arms 13 to accomplish the desired spraying action through the nozzles 14.

The residuum thus formed in the lower portion 30 of the vaporizer 1 overflows through the pipe 15 suitably connected to a pipe 19 and may be picked up by a pump 21 and forced through a line 22, controlled by a valve 23, to the coking still 2. The coking still 2 may be of the shell still type and may be fired underneath in a well known manner as shown in the drawing. While I have 35 shown one way of heating the still 2, any well known heating arrangement may be employed.

The still 2 may be partially filled with a suitable fusible material, preferably an easily fusible metal or alloy. A tin-lead alloy may be used in accordance with my invention although lead alone 40 may be used, if desired. In carrying out my invention the coking of the residuum is finished on the surface of the molten metal. The residuum to be coked may be introduced into the coking 45 still 2 by a line 24, controlled by a valve 25, and therein contacted with the bath of molten metal maintained therein. Upon contacting the bath of molten metal, heat is imparted to the residuum thereby decomposing it into coke. It will be evident that the coke as formed will be gradually displaced upwardly as it is being continuously added to below and will be finally forced through a dome 50 26 and connecting main 27 into the coke filter 3.

In accordance with my invention the residuum 55 may be fed below the surface of the molten metal to thereby cause it to rise upwardly therethrough. As shown in the drawing, suitable connections are provided for carrying out this method of operation. These connections may consist of a pipe 60 28, controlled by a valve 29, connected to a submerged distributing header 31. It will be evident from these connections that all or a portion of the residuum may be directly introduced into the body of molten metal maintained in the still 2 65 through the distributing header 31.

It may be desirable in operating in accordance 70 with my invention, and particularly when the residuum is being introduced into the still through line 24, to introduce a small quantity of cracked products from the cracking operation directly into the body of molten metal. As shown in the drawing, a pipe 32, controlled by a valve 33, may be suitably connected with the pipe 28 for introducing the cracked products into the distributing 75 header 31. This particular method of operation

is advantageous when all of the residuum is being introduced through the pipe 24 and also when a portion thereof is being introduced through the pipe 24 and another portion through the pipe 28 in that the cracked material in the form of vapors, gases and liquid products, on passing through the molten metal picks up additional heat therefrom and thus acts as a heat carrier for imparting this additional heat as well as portions of its own contained heat to the hydrocarbon material being 10 coked on the surface of the molten metal. The highly heated vapors and gases passing through the hydrocarbon material being converted into coke greatly lower the temperature at which the vaporizable material being formed in the coking 15 still 2 can be removed from the material being coked.

The coke particles produced in accordance with my invention are prevented from uniting into a solid mass which would completely fill the upper 20 part of the still by the violent agitation of the surface of the molten metal on which the coke rests. This violent agitation breaks up the masses into small units which may be allowed to accumulate in the free space of the still until it is 25 full or nearly full to the top. It will be evident that as additional residuum is being introduced through the lines 24 and/or 28 the coke will be gradually displaced upwardly and will be finally forced through the dome 26 and the connecting 30 main 27 into the coke filter 3 as previously explained.

Any liquid residuum not converted into coke and which may flow into the filter 2 with the coke 35 may be separated therein from the coke and may be returned to the pump 21 by means of a line 34 which may be joined to a liquid discharge line 35 connected to the lower portion of the coke filter 3. During normal operation of the process the residuum collected in the coke filter 3 may be 40 continuously withdrawn therefrom through the line 35 and reintroduced in a manner already described into the coking still 2.

My invention further provides an arrangement wherein a constant supply of residuum may be 45 introduced into the coking still regardless of whether a sufficient supply is being produced in the vaporizer 1. As shown in the drawing, an extraneous residuum or, if desired, a crude stock may be introduced into the coking still 2 through 50 a line 36 controlled by a valve 37 suitably connected to the branch line 24.

As shown in the drawing, the pipes 22 and 36, as well as the branch pipe 24 may be joined by means of a four way connection 38 to the line 55 28 which in turn connects with the distributing header 31 submerged in the fusible metal. By this arrangement it is possible to direct either or both the residuum and the crude oil that may be introduced through line 36 directly into the 60 molten material for vaporization and coking therein. The valves 23, 25, 29 and 37 are provided to control the distribution of liquids being introduced into the still through the several paths previously outlined.

In one manner of operation in accordance with 65 my invention, valves 29 and 37 may be kept closed while valves 23 and 25 are kept open to admit the liquid residuum to the coking still as already explained. When this method of operation is 70 being practiced, the control valve 33 may be opened to a greater or less extent to admit a predetermined amount of cracked products under pressure into line 28 to be passed through the header 31 submerged in the bath of molten metal. It 75

will be clear from the arrangement of pipes hereinabove explained that the residuum and/or the crude oil being introduced into the coking still 2 may follow several paths by obvious manipulation of the several valves disclosed in connection therewith.

The coke filter 3 which may also serve as a temporary storage vessel for the coke as formed, may be constructed as a cylindrical shell of any desired dimension. For instance, the shell may be some ten to fifteen feet in height and some ten to fifteen feet in diameter. The top of the coke filter 3 may be provided with a vapor discharge outlet 39 which connects with a suitable rectifying and fractionating tower, not shown, into which vapors evolved from the vaporizer 47 and the filter 3 may be passed. If desired, the coking still 2 may be provided with a separate vapor outlet which may be connected with the outlet conducting the vapors from the coke filter 3, the combined vapor streams being passed into the rectifying and fractionating column. The coke formed in the coking still 2 may be gradually forced by the continuous accumulation thereof through the coke transfer line or conduit 27 into the upper portion of the coke filter 3 as clearly shown in the drawing. While I have shown a particular arrangement for removing the coke from the coke still 2 into the coke filter 3, it is to be clearly understood that it is merely for illustrative purposes and any suitable means may be provided for accomplishing this purpose.

In accordance with my invention the coke may be accumulated in the coke still 2 until it reaches a point substantially at or near the dome 26. The coke thus accumulated may be flushed out of the coke still 2 through the conduit 27 into the coke filter 3 by a suitable flushing medium, such as hydrocarbon oil introduced into the still 2 through the pipes connected therewith. When operating in accordance with this method, it will be apparent that the coke formed in the still 2 may be intermittently removed by utilizing the flushing oil. The hydrocarbon oil used as a flushing medium and the coke removed from the coking still enter the coke filter 3 wherein the hydrocarbon flushing medium is filtered out and the coke permitted to dry or may be dried by extraneous sources such as a jet of steam or hot gas passing through the coke body collected on the filters in the coke filter 3.

A plurality of filter elements 41, Figure 3, in the form of thin metal sheets or bars of quadrant shape, are located in the lower half of the filter adjacent the walls thereof but in spaced relation thereto. The quadrant-shaped bars of the filter elements 41 may each be provided with two projecting lugs 42 one at each end thereof. The bars when assembled are arranged so that the lugs 42 bear against the sides of the filter shell to provide an annular space 43 between the filter elements and the sides of the filter. In this manner liquid can flow through the narrow apertures between adjacent bars. In order to form these apertures by providing a slight spacing between the abutting faces of the filter elements through which spaces the fluid may pass, the bars or elements 41 are provided with a plurality of very thin sheet metal washers 44, placed around tie bars 45 which are used for holding the filter elements together in stack formation. A washer may be placed between at least one face of each pair of abutting surfaces of the pack where the tie bars go through, the arrangement thus forming

thin channels between the spaced elements for the passage of liquid into the space 43.

Should any obstruction to the flow develop from deposit of material on the inner face of the filter elements during a filtering operation, this material may readily be dislodged and the elements restored to active service by admitting cracked stock, while under superatmospheric pressure, from the pipe 16 into the line 34 which leads into the annular space 43 of the filter. By introducing the cracked products in the manner described, any material obstructing the inner face of these openings may be dislodged. When carrying out this phase of the operation, valve 46 in line 41, which connects line 16 with line 34, will be opened to admit the cracked products to line 34 while valve 48 in the line 34 will be closed to prevent escape of the products into the residuum line 19. After the filter is thus cleared, the valves may be changed to their normal position for carrying out normal operation of the process.

In order to dump the collected coke in the filter there is provided a removable door 49 through which the coke may be discharged either into a suitable tram or into a chute such as is used for ash removal, or any other suitable means.

Retaining rings 51 and 52 at the top and bottom of the filtering stack, respectively, close the space 43 and in connection with the tie bars 45 fix the filtering stack firmly in its proper place in the filter shell from which it may be easily removed for cleaning and repairs when necessary.

While I have illustrated and described a single coke filter associated with the coking still 2, it is to be clearly understood that two or more such filters may be provided. In this manner while one is being filled another may be emptied and cleaned without stopping the operation of the still. The use of more than one coke filter in practicing my invention is important as the volume of coke to be handled is large. Preferably two such filters should be used in order to insure a short transfer line 27 between the still 2 and the filter 3, each filter being to the side of the still and in line with the delivery dome 26 which affords a symmetrical arrangement of the apparatus.

From the foregoing it will be apparent that I have invented a novel method of coking hydrocarbon oils with the necessary apparatus for carrying out my invention. The use of molten metal as a heating medium is quite advantageous in accordance with my invention in that it insures that the distribution of heat throughout the body of hydrocarbon being coked will be as nearly uniform as possible and at the same time will prevent and possibly avoid overheating the still bottom as would likely occur if such a heating medium were not used as a protective means.

While my invention has been described in connection with coking of residual oil produced in the cracking of hydrocarbon oil, it is to be clearly understood that other carbonizing material may be coked in accordance therewith. Carbonaceous material, preheated if desired, may be carbonized in accordance with my invention by introducing it through a line comparable with either 24 or 28, the latter of which is connected to the distributing header 31 or in any other suitable manner falling within the scope of my invention.

Thus, my invention contemplates the coking of such materials as bituminous coal, peat, lignite, etc. When such solid carbonaceous material is to be treated it may be desirable to employ a different means for charging such material to the coking still. Instead of the pipes 24 and 28, a screw or chain-type feeder may be employed to feed the material to be coked. It will also be understood that heavy liquid hydrocarbon material may be coked or carbonized simultaneously with such solid carbonaceous material.

If desired, the dome 26 may extend the entire width of the coking still 2. It may be desirable to curve the dome from its point of junction with the coke still in an even curve to the top of the filter 3 where the outlet of the dome may be connected. In this manner, abrupt turns in the passage through which the coke may be removed are eliminated.

Obviously, many modifications and variations of the invention, as hereinbefore set forth, may be made without departing from the spirit and scope thereof, and therefore, only such limitations should be imposed as are indicated in the appended claims.

I claim:

1. A process for coking hydrocarbon oils which comprises maintaining a body of heavy oil in a vaporizing zone, continuously introducing a highly heated oil, at a temperature above the temperature of the body of oil, below the surface thereof to heat the body of oil to a temperature sufficiently high to accomplish distillation of the body of oil, causing the highly heated oil to pass through said body of oil at high velocity so as to continuously blow portions of the same as a spray into the free space of the vaporizing chamber, the unvaporized portion of said spray continuously falling back onto the body of oil from whence it came, withdrawing residual products from said vaporizing zone and conducting them while in a heated condition to a coking zone, and contacting said residual products in said coking zone with highly heated molten metal to convert same into a coke residue.

2. A process for coking hydrocarbon oils which comprises maintaining a body of heavy oil in a vaporizing zone, continuously introducing a highly heated oil, at a temperature above the temperature of the body of oil, below the surface thereof to heat the body of oil to a temperature sufficiently high to accomplish distillation of the body of oil, causing the highly heated oil to pass through said body of oil at high velocity so as to continuously blow portions of the same as a spray into the free space of the vaporizing chamber, the unvaporized portion of said spray continuously falling back onto the body of oil from whence it came, withdrawing residual products from said vaporizing zone and conducting them while in a heated condition to a coking zone, and

passing said residual products entering said coking zone through a body of molten metal maintained therein at a temperature higher than the temperature of said entering residual products to thereby impart additional heat to said residual products and convert them to a coke residue in the coking zone.

3. A process for coking hydrocarbon oils which comprises maintaining a body of heavy oil in a vaporizing zone, continuously introducing a highly heated oil, at a temperature above the temperature of the body of oil, below the surface thereof to heat the body of oil to a temperature sufficiently high to accomplish distillation of the body of oil, causing the highly heated oil to pass through said body of oil at high velocity so as to continuously blow portions of the same as a spray into the free space of the vaporizing chamber, the unvaporized portion of said spray continuously falling back onto the body of oil from whence it came, withdrawing residual products from said vaporizing zone and conducting them while in a heated condition to a coking zone, passing said residual products entering said coking zone through a body of molten metal maintained there- 25 in at a temperature higher than the temperature of said entering residual products to thereby impart additional heat to said residual products and convert them to a coke residue in the coking zone, removing said coke residue from the coking zone 30 and conducting it to a coke filter to separate out fluid remaining therein.

4. A process for coking hydrocarbon oils which comprises maintaining a body of heavy oil in a vaporizing zone, continuously introducing a highly heated oil, at a temperature above the temperature of the body of oil, below the surface thereof to heat the body of oil to a temperature sufficiently high to accomplish distillation of the body of oil, causing the highly heated oil to pass through said body of oil at high velocity so as to continuously blow portions of the same as a spray into the free space of the vaporizing chamber, the unvaporized portion of said spray continuously falling back onto the body of oil from whence it came, withdrawing residual products from said vaporizing zone and conducting them while in a heated condition to a coking zone, passing said residual products entering said coking zone through a body of molten metal main- 50 tained therein at a temperature higher than the temperature of said entering residual products, introducing oil at cracking temperature into intimate contact with the residual products entering said coking zone, and decomposing the residual products to a coke residue in said coking zone by the heat imparted thereto from the body of molten material and the oil at cracking temperature intimately contacted with said residual products.

DONALD L. THOMAS.
